UNITED STATES PATENT OFFICE.

EMIL F. BIRKHOLZ, OF EDEN, WISCONSIN, ASSIGNOR OF ONE-THIRD TO
FREDERICK WOLF, OF SAME PLACE.

MANUAL BOAT PROPULSION.

SPECIFICATION forming part of Letters Patent No. 537,435, dated April 16, 1895.

Application filed November 17, 1894. Serial No. 529,123. (No model.)

To all whom it may concern:

Be it known that I, EMIL F. BIRKHOLZ, a citizen of the United States, and a resident of Eden, in the county of Fond du Lac and State 5 of Wisconsin, have invented certain new and useful Improvements in Propelling Boats; and I do hereby declare that the following is a full, clear, and exact description thereof.

My invention has for its object to provide 10 a boat with simple, economical and effective propelling apparatus especially designed for operation by manual power, the peculiarities of construction and combination of parts embodied in said apparatus being hereinafter 15 specified with reference to the accompanying drawings and subsequently claimed.

In the drawings: Figure 1 represents my improved boat propelling apparatus as viewed in section on line 1—1 of the succeeding figure; Fig. 2, a side elevation of the same the propeller-wheel casing in this figure being in section on line 2—2 of the preceding figure, and Fig. 3, a detail view illustrating means for clutching a crank on a drive-shaft embodied in said apparatus.

Referring by letter to the drawings, A represents the bottom of a boat provided with suitable openings covered by casings B, and these casings are provided with bearings b for 30 a shaft C that carries propeller-wheels the latter being within said casings and operating through the bottom openings of the boat.

A pinion E fast on the wheel shaft C is in mesh with a gear-wheel F carried by a counter-shaft G that turns in standards H rising from the casings B, and the gear-wheel has a pinion-hub I in mesh with another gear-wheel J fast on a drive-shaft K, the bearings c for the latter shaft being lateral extensions of arms 40 L that are loose on the counter-shaft to be thus in pivotal connection with said standards.

The lower ends of the arms L are provided with segmental slots d, and set-screws M engaging the slots and the standards H hold 45 said arms in pivotal adjustment.

The drive-shaft K is shown as provided with ratchet-wheels N, and cranks P loose on said shaft have spring-controlled dogs e that automatically engage with the ratchet-wheels.

50 The cranks being in clutch connection with

the ratchet wheel's rotary motion may be readily imparted to the drive-shaft, and when not in use said cranks will automatically assume a depending vertical position so as to be as much as possible out of the way. However 55 I do not wish to be understood as confining myself to loose cranks in clutch-connection with the drive-shaft, as rigid cranks may be employed.

Rotary motion imparted to the drive-shaft 60 is transmitted to the propeller-wheels by means of the gearing above specified, and said drive-shaft being supported by pivotally adjustable arms, its height may be readily regulated, within certain limits, to suit the convenience 65 of those operating the cranks.

As herein shown, I prefer to have the propeller-wheels in the form of drums D provided with peripheral blades f, each of which is oblique to the axis of the relative drum 70 and flanked at each end by a right-angle flange g, the flange at one end being extended in a direction opposite that at the other as best illustrated by the elevation of one of said wheels in Fig. 2. These propeller wheels will 75 turn in weeds without clogging, and in action they draw water from the sides of the boat toward the center whereby said boat tends to lift and the draft is lightened.

In addition to the advantages just specified, 80 the preferred form of propeller-wheels will not wind water, and in case their blades strike bottom said wheels will operate as traction-wheels to propel the boat over shoal places.

The herein described gearing may be utilized 85 in connection with propeller wheels of various designs, and said wheels of the form herein shown may be driven by various arrangements of gearing.

Having thus described my invention, what 90 I claim as new, and desire to secure by Letters Patent, is—

1. The combination of a boat and incased propeller-wheels extending through the bottom of the same, with a gearing comprising 95 a pinion on a shaft carrying the propeller-wheels, a counter-shaft having its bearings in standards rising from the wheel-casings, a gear-wheel fast on the counter-shaft and provided with a pinion-hub, arms pivotally ad- 100

justable on the standards, a drive-shaft supported by the arms, and a gear wheel fast on the drive-shaft in position to mesh with said pinion-hub of the former gear-wheel, substantially as set forth.

2. The combination of a boat and incased propeller-wheels extending through the bottom of the same, a gearing comprising a pinion on a shaft carrying the propeller-wheels, 10 a counter-shaft having its bearings in standards rising from the wheel-casings, a gear-wheel fast on the counter-shaft to mesh with the propeller-shaft pinion and provided with a pinion-hub, a drive-shaft supported in bearings connected to the aforesaid standards; a

gear-wheel fast on the drive-shaft in position to mesh with said pinion-hub of the former gear-wheel, ratchet-wheels rigid on said drive-shaft, cranks loose on the aforesaid drive-shaft, and spring-controlled dogs on the cranks engaging the ratchet-wheels, substantially as set forth.

In testimony that I claim the foregoing I have hereunto set my hand, at Fond du Lac, in the county of Fond du Lac and State of Wisconsin, in the presence of two witnesses.

EMIL F. BIRKHOLZ.
